United States Patent Office

Des. 182,960
Patented June 3, 1958

182,960

ADJUSTABLE MOUNT FOR SIGHT UNIT AND CAMERA

John E. Huber, Delhi Township, Hamilton County, Ohio, assignor to Huber Industries, Inc., Cincinnati, Ohio, a corporation of Ohio

Application February 13, 1956, Serial No. 40,133

Term of patent 14 years

(Cl. D61—1)

FIG. 1

FIG. 2

I claim:

The ornamental design for an adjustable mount for sight unit and camera, as shown.
